UNITED STATES PATENT OFFICE.

JOSEPH STUBBERS, OF COVINGTON, KENTUCKY, ASSIGNOR TO THE INCANDESCENT LIGHT & STOVE COMPANY, OF CINCINNATI, OHIO, A CORPORATION.

MANTLE-HOLDER FOR GAS-BURNERS.

SPECIFICATION forming part of Letters Patent No. 777,267, dated December 13, 1904.

Application filed June 17, 1904. Serial No. 213,009. (No model.)

To all whom it may concern:

Be it known that I, JOSEPH STUBBERS, a citizen of the United States, residing at Covington, in the county of Kenton and State of Kentucky, have invented certain new and useful Improvements in Mantle-Holders for Gas-Burners, of which the following is a specification.

My invention relates to an improved mantle-holder for gas-burners.

The features of my invention are more fully set forth in the description of the accompanying drawings, forming a part of this specification, in which—

15 Figure 1 is a side elevation of burner and supply-pipe with my improved mantle-holder. Fig. 2 is a top plan view of the same with the burner omitted and mantle-supporting stem in section.

20 1 represents the gas-supply tube. 2 represents the burner-tube parallel therewith. 3 represents the elbow joining them.

4 represents a lug projected from the elbow or supply-pipe. 5 represents another lug projected from the elbow in a central vertical line with the burner-tube. It is provided with the vertical groove 6. The vertical notch 7 lies between and is formed by the vertical walls 14 15 (see Fig. 2) on the outer end of the lug

30 5. Wall 14 is projected beyond the wall 15 and is provided with the orifice 16 opposite to a notch 7 (see Fig. 1) in the vertical wall 15. The notch 7 and the orifice 16 form a horizontal groove or channel transverse to the vertical groove or channel 6, through which horizontal channel the spring 9 passes, the inner end of said spring being fixed to a lug 4. The lower end of the mantle-supporting stem 11 is placed in the vertical groove 6 and 40 held there by the frictional engagement and the tension of the spring 9, which passing through notch 7 and orifice 16 bridges the vertical groove 6 transversely and gives the spring 9 clamping access to the stem 11, supporting it firmly in the vertical groove 6.

45 10 represents the mantle having the vertically-supporting stem 11, the lower end of

which is inserted into the vertical groove 6, against the inner vertical wall of which it is clamped by the spring 9, as above described. 5c

In operating the spring 9 is pushed out, the stem 11 is inserted in place in the groove 6, and the spring released. This avoids the use of screws, which bend the mantle-supporting stem, throwing the same out of vertical alignment with the burner. The inner wall of the vertical groove 6 constitutes a vertical bearing, which insures that the mantle will be held in true vertical position by the clamping action of the spring 9. This tension-clamp is easier handled than a screw-clamp, it insures a vertical position, it does not bend or indent the mantle-supporting screw, and it does not jar the mantle in inserting. 65

Having described my invention, I claim—

1. In combination with a gas-burner, mantle and supporting-wire, a lug projected from the side of the burner in vertical line with the center, having a vertical groove with a horizontal notch, a horizontal spring fixed at one end to the burner, extending through said horizontal notch and across the vertical groove, bearing against and clamping the mantle-supporting stem to the inner wall of the groove, 75 substantially as described.

2. In combination with the gas-burner, mantle and supporting-wire, a lug projected from the side of the burner in vertical line with the center having a vertical groove with horizontal notches formed in the opposite walls of said vertical groove, a spring attached at one end to the burner and extending horizontally through said notches bridging said vertical groove, and clamping the stem of the mantle-support against the inner, vertical wall of said groove, substantially as described. 85

In testimony whereof I have hereunto set my hand.

JOSEPH STUBBERS.
